UNITED STATES PATENT OFFICE.

JACKSON O. BELKNAP AND ORVILLE F. CAWTHON, OF MOBILE, ALABAMA.

CAR-SIGNAL.

SPECIFICATION forming part of Letters Patent No. 440,127, dated November 11, 1890.

Application filed April 26, 1890. Serial No. 349,680 1/2. (No model.)

To all whom it may concern:

Be it known that we, JACKSON O. BELKNAP and ORVILLE F. CAWTHON, citizens of the United States, residing at Mobile, in the 5 county of Mobile and State of Alabama, have invented certain new and useful Improvements in Car-Signals, of which the following is a specification, reference being had therein to the accompanying drawings.

10 This invention relates to certain new and useful improvements in audible car-signals designed with special reference for use on street-railway cars, whereby the approach of the car will be known by the ringing of the bell.

15 Letters Patent No. 421,227 were granted to us February 11, 1890, for car-signals, in which the connection of the bell with the axle was a rigid one, so that the ringing was effected

20 by the vibrations of the clapper as the bell turned over and over with the revolutions of the axle.

25 The present invention involves a flexible connection between the bell and the axle, whereby the bell itself as well as the clapper will be capable of vibration as it travels around with the axle.

30 The present invention also involves the provision of a spring or yielding stop, which limits the vibration of the bell and causes such a reaction as to increase the number of taps by the clapper.

35 In the accompanying drawings, forming a part of this specification, and on which like reference-letters indicate corresponding parts, Figure 1 represents a sectional view of a car-axle, a bell, and intermediate connections involving our invention; Fig. 2, an elevation of the same parts; Fig. 3, a side view of the bell 40 and attachments and a section of the axle; and Fig. 4, a similar view to Fig. 2, save that the bell is in the position of just passing over the axle, a modified form of the clamp being shown in this view.

45 The letter A refers to a car-axle of the ordinary or any approved kind, the letter B a portion of a car-wheel, and the letter C a part of the car-track. A clamp consisting of halves D and E, each having lugs F and G and F' 50 and G', is clamped to the axle by bolts and nuts or screws H and I.

In the lugs G' eyes J are formed for the reception of a pivot-bolt K, upon which the bell is hung. This clamp may be made of sheet or cast metal, malleable iron being preferred. 55

In Fig. 2 the lug G' is shown as having an eye at each side with a space between them, in which the head L of the bell is placed. In Fig. 4 the clamp is narrower, and the eye J is extended across the entire width of the lug 60 G' and the head L placed to one side of the eye instead of between the two eyes. In either case the connection is formed by the bolt K passing through the head L of the bell. This connection between the bell and the axle 65 is a pivotal one—that is to say, the clamp rigidly grasps the axle and the bell is pivotally connected with the clamp.

The bell itself is designated at M, and is of the ordinary type so far as concerns the formation of the body thereof. By preference the head L is formed separate from the bell and provided with a threaded shank O, held by a nut P and having an opening to receive the wire Q of the clapper R. A yielding or 70 spring stop is preferred as a means of limiting the vibrations or swinging of the bell. A convenient form of such stop is shown at S, being in the form of a spring-bow, secured to the bell by being placed between the head L 75 and the body of the bell, and having the shank O passed therethrough. The ends of this spring-stop are adapted to strike against the clamp or axle and arrest the vibration of the bell. The reaction of the spring causes 80 a vibration of the bell in the opposite direction from that in which it is arrested, resulting in multiplying the number of taps given by the clapper. This increases the audibility 85 of the bell and will enable a smaller and less 90 expensive bell to attract as much attention as a larger and more costly one.

We wish to be understood as contemplating the omission of the spring-stop in some instances, but preserving the pivotal or vibratory connection of the bell. Again, when a spring is used, it may act on one or both sides of the connection of the bell, and it may have a different form from that shown and described. We do not wish to be understood 95 as limiting ourselves as to the arrangement or form in this respect, nor to other matters 100

of detail, which will be obvious to the mechanic in view of the teachings of this specification.

Having thus fully described our invention, 5 what we claim as new, and desire to secure by Letters Patent, is—

1. The combination, with a car-axle and an audible signal actuated thereby, the latter consisting of a bell, of a pivot therefor on which 10 the bell has a movement as the axle revolves, and a pivot-support for the bell connected to the axle.

2. The combination, with a car-axle and an audible signal actuated thereby, consisting 15 of a bell, of a pivot therefor on which the bell has a movement as the axle revolves, a support for the said pivot connected to the axle, and a spring-stop acting to limit the vibrations of the bell on its pivot and to cause a 20 reaction to multiply the number of taps of the clapper.

3. The combination, with a car-axle, of an audible signal consisting of a bell, a two-part clamp secured upon the axle, and a pivot for 25 the bell carried by the said clamp, the bell having a movement on the pivot as the axle revolves.

4. The combination, with a car-axle and an audible signal actuated thereby, consisting of a bell, of a two-part clamp secured to the axle, 30 a pivot carried by the clamp and on which the bell is hung and has a movement as the axle revolves, and a spring-bow constituting a yielding stop and adapted to limit the vibrations of the bell and effect a reaction. 35

5. The combination, with a clamp, of a bell, a pivot for the bell on the pivot carried by the clamp, and a spring-stop adapted to limit the vibrations of the bell with respect to the clamp as the axle revolves. 40

6. The combination, with a two-part clamp, of an eye formed in one of said clamps, a pivot-bolt in said eye, a bell loosely hung on said bolt, on which it has a movement as the axle revolves, and a bow-spring secured to the bell 45 about the center, leaving projecting spring-arms.

In testimony whereof we affix our signatures in presence of two witnesses.

JACKSON O. BELKNAP.
ORVILLE F. CAWTHON.
